SLIPPER

Nickolas F. Fillips, Pittsburgh, Pa., assignor to Sani-Foam Products, Inc., Pittsburgh, Pa., a corporation of Pennsylvania

Application July 10, 1956, Serial No. 42,189

Term of patent 3½ years

(Cl. D7—7)

Fig. 1 is a plan view of a slipper embodying my invention;

Fig. 2 is a side view thereof;

Fig. 3 is an end view; and

Fig. 4 is a cross section of the sole of the slipper, taken on the line IV—IV of Fig. 1.

I claim:

The ornamental design for a slipper, as shown.
